THERMAL VALVE

Jay Lawrence Seat, Fairfield, Conn., assignor to
Mergenthaler Linotype Company, a corporation
of New York

Application May 18, 1933, Serial No. 671,618

5 Claims. (Cl. 169—41)

This invention relates to thermal valves, and especially to thermal valves for use in connection with fire extinguishing systems of the type disclosed in my co-pending application, Serial 5 No. 621,223 filed July 7, 1932, which has matured into Patent 2,025,782 wherein a fire extinguishing fluid, such as carbon tetrachloride, is normally stored in the system and is released therefrom when the temperature in the vicinity of 10 a valve increases to a predetermined degree.

Heretofore, thermal valves have been designed for use in connection with fire extinguishing systems wherein water is used as the fire extinguishing fluid, and, in general, they 15 comprise a single tubular section which is provided at one end with a deflector and at the other end with a valve arrangement which is normally maintained closed against the action of a spring by a fusible element. When the temperature in the vicinity of a thermal valve of 20 this sort increases to a predetermined degree, the fusible element melts, thereby releasing the spring and automatically opening the valve, and when the valve is thus opened the fire extinguishing fluid is forced upwardly through the tubular section and against the deflector which 25 serves to break up the stream into a spray and to direct the spray thus formed downwardly toward a protected area beneath. In systems of 30 this sort the water supply is substantially unlimited, hence it is common practice to so design the thermal valves that large quantities of water are quickly discharged therefrom when they are opened. In systems such as is disclosed in my above noted patent, however, the 35 quantity of fire extinguishing fluid is limited and must be used sparingly, consequently such thermal valves are unsatisfactory. Furthermore, during the installation of fire extinguishing systems it is frequently desirable to install 40 the thermal valves so that they open from the bottom rather than from the top of the distribution pipe, and when this is done with thermal valves, as heretofore designed, the fire extinguishing fluid instead of being directed downwardly by the deflector toward the area to be 45 protected is directed upwardly and then outwardly away from the area beneath.

An object of the present invention is to provide 50 a thermal valve which automatically opens when the temperature in the vicinity thereof increases to a predetermined degree.

Another object of the invention is to provide 55 a thermal valve wherein the fire extinguishing

fluid is sprayed directly therefrom without the aid of the deflector when the valve opens.

Another object of the invention is to provide a thermal valve which is adapted to open either from the top or from the bottom of a distribution pipe of a fire extinguishing system. 5

Still another object of the invention is to provide a thermal valve wherein the discharge of fire extinguishing fluid therefrom may be varied.

In accordance with the present invention, the 10 above, and other objects, are attained by means of a tubular valve frame or casting, one end of which is adapted to be connected into a distribution pipe of a fire extinguishing system. A valve is positioned in this end of the tubular 15 frame and it is normally maintained closed against the action of a spring by a fusible element. The other end of the tubular frame terminates in a removable discharge head which is provided with a plurality of small discharge 20 openings or ports. When the temperature in the vicinity of the valve increases to a predetermined degree the fusible element melts, thereby releasing the spring and automatically opening the valve. When the valve is open, the fire 25 extinguishing fluid is forced through the tubular frame into the removable discharge head from whence it is forced outwardly in a desired direction through the small discharge openings or ports without the aid of a deflector. 30

In the accompanying drawing, the invention is shown merely in preferred form and by way of example, but obviously many changes and variations may be made therein and in its mode of application which will be comprised within its 35 spirit. It should, therefore, be understood that the invention is not limited to any specific form or embodiment, except in so far as such limitations are specified in the claims.

Referring to the drawing:

Fig. 1 is an elevational view, partially in section, of a valve embodying the principle of the present invention;

Fig. 2 is a side elevation, in section, taken along the line 2—2 of Fig. 1;

Fig. 3 is a sectional view taken along the line 3—3 of Fig. 1; and

Fig. 4 is a sectional view taken along the line 4—4 of Fig. 1.

As shown, the thermal valve comprises a frame 50 or casting having two oppositely disposed U-shaped tubular members 10 and 11, which terminate at their lower ends in a single tubular valve section 12 and at their upper ends in a single tubular discharge section 13. The lower tubular 55

valve section 12 is provided with external screw threads 14 to permit the device to be connected into a distribution pipe of a fire extinguishing system. A bushing 15 is threaded into the lower 5 end of the valve section 12, the lower face of the bushing 15 being provided with a transverse slot 16 which is adapted to receive the end of a suitable turning tool, to aid in the assembly of this portion of the structure. The upper face of the 10 bushing 15 is tapered to provide a seat for the tapered lower end of a valve 17. A bushing 18 is threaded into the upper end of the valve section 12 and it serves as a bearing for a valve stem 20 which is carried by the valve 17, and to aid 15 in the assembly of this portion of the structure the bushing 18 is provided with a plurality of holes 19 which are adapted to receive the end of a suitable turning tool. A collar 21 is secured, as by a pin 21a, to the lower end of the valve 20 stem 20 adjacent the upper face of the valve 17. A spring 22 which is positioned about the valve 17 between the collar 21 and the bushing 15 normally tends to force the valve 17 upwardly to establish communication between the lower and 25 the upper ends of the tubular frame, and to render the bearing bushing 18 fluid tight when the valve is so opened a ring of packing material 23 is provided on the upper face of the collar 21.

In accordance with the present invention, 30 means are provided to complete an electrical circuit when the valve is so opened, and to this end the upper end of the valve stem 20 is reduced and it is provided with a contact plate 24 which is maintained in place thereon by a pin 25. A contact member 49 is positioned above the contact plate 24 and it is adapted and arranged to be engaged thereby when the valve is opened. This contact member 49 comprises the head of a stud 50, the shank or unthreaded portion of which 35 is embedded in a block of insulating material 51 secured to the tubular member 11 by a bolt 52 and the threaded or end portion of which is secured to the positive side of an electrical circuit by means of a suitable insulated conductor.

The valve 17 is normally maintained closed 40 against the action of the spring 22 by a fusible element 28 which is positioned between the oppositely disposed ends of the valve stem 20 and a stud 26 which is threaded into a recess formed 45 in the frame directly above the valve stem 20, and to prevent displacement of the fusible element its ends are tapered and the oppositely disposed end faces of the valve stem 20 and the stud 26 are slightly concaved to receive the tapered ends of the fusible element. The head of the stud 26 is provided with a plurality of holes 50 which are adapted to receive the end of a turning tool to permit adjustment of the stud when installing the fusible element.

The fusible element 28 comprises an inverted 55 U-shaped female section 30, an inverted T-shaped male section 32 and a connecting inverted U-shaped central section 31. The three sections are desirably pressed together, and to 60 hold them in place the engaging edges of the male and female sections are provided with serrations 33. The male and female sections 30 and 32, are adapted and arranged to remain unaffected by elevated temperatures, but the connecting central section 31, is adapted and arranged to fuse or melt when the temperature in the vicinity thereof increases to a predetermined degree, and when the connecting central section 31 does fuse or melt the inverted T-shaped male section 32 is forced upwardly into 65

the inverted U-shaped female section 30 by the spring 22, as shown in Fig. 2. Under such conditions the force tending to maintain the valve closed against the action of the spring 22 is removed and, as a result, the valve is automatically 5 opened. While this type of fusible element is desirable, equally favorable results may be obtained with other type fusible elements, the essential feature in all cases being that the element shall normally maintain the valve closed against 10 the action of the spring and shall release the spring to open the valve when the temperature in the vicinity thereof increases to a predetermined degree.

The discharge section 13 terminates in a reversible discharge head 41 having a plurality of small discharge openings or ports 48 through which the fire extinguishing fluid is forced when the valve 17 is open. In most instances it is desirable that the fire extinguishing fluid be ejected 20 either upwardly or downwardly, and for this reason the outer face of the discharge head is rounded or V-shaped and the ports open therefrom between the top or bottom face, depending on the position of the head, and a horizontal 25 line drawn through the center of the head. It is evident, however, that equally favorable results may be obtained by other arrangements as, for example, by having the discharge ports open from a straight inclined face. 30

The discharge head 41 is removably connected to the discharge tubular section 13, and to this end the upper outer end of the discharge section 13 is reduced to form a shoulder 35. A ring of suitable packing material 39 is positioned on 35 the shoulder 35 and it carries a flanged clamping ring 40 on which the lower inner rim of the discharge head 41 rests. The upper inner rim of the discharge head 41 carries a similar flanged clamping ring 42 which, in turn, carries a similar 40 ring of packing material 43. A plug 38 is threaded into the upper end of the tubular section 13 and it serves to clamp the inner rims of the discharge head 41 between the clamping rings 40 and 42, and to maintain the inner rims of the discharge 45 head in spaced relation a U-shaped annular spacing member 44 is positioned therebetween. The discharge section 13 and the U-shaped spacing member 44 are provided with a plurality of openings 45 and 46 respectively to establish communication between the tubular member 13 and the head 41. 50

In operation, when the temperature in the vicinity of a thermal valve increases to a predetermined degree the central section 31 of the fusible element 28 melts, thereby releasing the spring 22 which acts to force the valve 17 and the associated valve stem 20 upwardly. As the valve 17 is forced upwardly communication between the opposite ends of the tubular frame is established 60 and as a result the fire extinguishing fluid, which is normally maintained in the distribution pipe under pressure, is forced upwardly through the lower tubular valve section 12, the two oppositely disposed central members 10 and 11, the upper tubular discharge section 13, and thence outwardly through the openings 45 and 46 into the discharge head 41 from whence it is forced outwardly and downwardly through the discharge ports 48. 70

As the valve stem 20 is forced upwardly it carries the contact plate 24 into engagement with the head of the conducting stud 49 thereby completing an electric circuit from the positive side through the device to the distributor pipes which 75

are connected to the negative side of the circuit. The circuit thus closed may be utilized for a number of purposes as, for example, to ring an alarm or to start a compressor to supply pressure to the system.

5 In the event it is desired to have the fire extinguishing fluid forced outwardly and upwardly from the head, or in the event it is desired to have the valve open from the bottom of the distribution 10 pipe and the fire extinguishing fluid forced outwardly and downwardly therefrom, the discharge head 41 may be removed and reversed. Also, in the event it is desired to vary the quantity of fire 15 extinguishing fluid which is discharged when the valve is open, the discharge head may be removed and replaced by a discharge head having a greater or less number of discharge openings or ports.

20 After a valve has been opened and it is desired to replace the fusible element to reclose the valve, the stud 26 is backed off to permit the insertion of the tapered ends of the fusible element between the oppositely disposed concaved ends of the screw 26 and the valve stem 20 after which the 25 stud 26 is lowered to securely clamp the fusible element in place.

I claim:

30 1. A thermal valve comprising a tubular frame, one end of which contains a valve and the other end of which terminates in a reversible discharge head, and a fusible element normally maintaining said valve closed, said head being adapted and arranged to discharge a plurality of streams upwardly beyond said valve when in one position and downwardly beyond said valve when the position thereof is reversed.

35 2. A thermal valve comprising a tubular frame, one end of which contains a valve and the other end of which terminates in a reversible discharge head, means normally tending to force said valve open to establish communication between the ends of said tubular frame, and a fusible element normally maintaining said valve closed against 40 the action of said first mentioned means, said head being adapted and arranged to discharge a plurality of streams upwardly beyond said thermal valve when in one position and downwardly

beyond said thermal valve when the position thereof is reversed.

3. A thermal valve comprising a tubular frame, one end of which contains a valve and the other end of which terminates in a reversible discharge head, a spring normally tending to force said valve open to establish communication between the opposite ends of said tubular frame, and a fusible element normally maintaining said valve closed against the action of said spring, said head 10 being adapted and arranged to discharge a plurality of streams upwardly beyond said thermal valve when in one position and downwardly beyond said thermal valve when the position thereof is reversed. 15

4. In a thermal valve, the combination of a plurality of U-shaped members which merge at their opposite ends into single end tubular sections, a valve positioned in one of said end sections, a valve stem carried by said valve and 20 extending through the junction of the members which merge into the section in which said valve is positioned, an adjustable member positioned in the junction of the members which merge into the other of said end sections, a spring normally 25 tending to force said valve open to establish communication between said end sections, and a fusible element for maintaining said valve closed against the action of said spring, said element being positioned between said valve stem and 30 said adjustable member.

5. A thermal valve comprising two oppositely disposed tubular members which merge at their opposite ends into single end tubular sections, a reversible discharge head opening from one of 35 said end sections, a valve positioned in the other of said end tubular sections, a valve stem carried by said valve and extending through the junction of the members which merge into the end section in which the valve is positioned, a stud 40 positioned in the junction of the members which merge into the other of said end sections, a spring normally tending to force said valve open, and a fusible element for maintaining said valve closed against the action of said spring, said element 45 being positioned between said valve stem and said stud.

JAY LAWRENCE SEAT.
